MESNE ASSIGNMENTS, OF ONE-FOURTH TO PATRICK OLSON AND ONE-HALF TO
JOSEPH B. ROONEY, BOTH OF INTERNATIONAL FALLS, MINNESOTA

GARAGE DOOR OPERATING MECHANISM

Application filed February 14, 1930. Serial No. 428,481.

This invention relates to door operating mechanisms and more specifically to devices for opening and closing garage doors and has for an object to provide novel means for opening the doors from the exterior of the garage without getting out of the vehicle.

A still further object is to provide an extremely strong and durable device of this character which is composed of a few simple parts that will not easily get out of order and which will be mounted for the most part interiorly of the garage so as to be protected from exposure to the weather.

With the above and other objects in view the invention consists in certain novel details of construction and combinations of parts hereinafter fully described and claimed, it being understood that various modifications may be resorted to within the scope of the appended claims without departing from the spirit or sacrificing any of the advantages of the invention.

In the accompanying drawings forming part of this specification,

Figure 1 is an underneath view of my improved device in position to maintain the doors closed and shown by dotted lines in position to swing the doors open,

Figure 2 is an enlarged underneath view of the device with the bottom plate and other parts removed,

Figure 3 is an enlarged section taken on the line 3—3 of Figure 1,

Figure 4 is a fragmentary perspective view showing the fulcrum bars, sliding pivot and guides of the operating levers,

Figure 5 is an enlarged side elevation of the rope reel located exteriorly of the garage for operating the door-opening device, and

Figure 6 is a cross-sectional view on the line 6—6 of Figure 3.

Referring now to the drawings in which like characters of reference designate similar parts in the various views, 10 designates the roof, 11 the side walls, and 12 the outwardly opening hinged doors of a garage. As is usual in garage construction there is a horizontal sill 13 forming the top of the door frame and I preferably attach my improved door opening and closing device to

this sill so that the parts will be housed within the garage and protected from the weather.

In carrying out the invention I provide a bottom plate 14 which is bolted as shown at 15 to the bottom face of the sill 13. The plate is preferably square in outline and is provided as best shown in Figure 3 with a longitudinal slot 16, the purpose of which will presently appear. A top plate 17 is disposed parallel with the bottom plate and interposed between the top and bottom plates are spacing blocks 18. Bolts 19 are passed through the plates and spacing blocks to rigidly secure the plates together in spaced relationship as best shown in Figure 3. The parts just described form a support for the door operating mechanism about to be described.

A shaft 20 is journaled in an opening in the top plate 17 and projects at both ends beyond the opposite faces of the plate. A ratchet disc 21 is keyed to the lower end of the shaft, and a rope pulley 22 is mounted loose upon the upper end of the shaft. A stop collar 23 holds the pulley on the shaft. A rope 24 is secured at one end to an eye 25 in the channel of the pulley and forms means for rotating the pulley through half a revolution counter-clockwise. A helical spring 26 surrounds the shaft 20, one end of this spring being attached to the plate 17 and the other end of the spring being attached to the pulley 22. This spring returns the pulley to inactive or released position after each rotation thereof by the rope 24.

The above mentioned ratchet disc 21 is provided in the peripheral edge with two pairs of ratchet teeth 27—28 and 29—30. A pawl 31 is pivoted on the pulley 22 and normally held in the tooth 29 by a spring 32 whereby when the pulley is turned the ratchet disc will be locked to and moved as a unit with the rope pulley. A pawl 33 is pivoted on the plate 17 and is held by a spring 34 to engage the ratchet tooth 30 on the ratchet disc and prevent rotation of the ratchet disc in a clockwise direction.

The purpose of the two pairs of slots is as follows. When the rope pulley 22 is turned through approximately half a revolution the

disc 21 is likewise turned by means of the pawl 31 on the pulley and thereupon the tooth 28 and tooth 27, as best shown in Figure 2, will move counter-clockwise and assume 5 the positions occupied by the teeth 29 and 30. The pawl 33 immediately drops in back of the tooth 27 and prevents retrograde movement of the disc. Upon release of the 10 rope 24 the spring 26 immediately operates to return the rope pulley to its original position. The pawl 31 on the rope pulley then drops in back of the tooth 28 and the device is ready to be again operated.

A pitman 35 is pivoted to one side face 15 of the disc 21 as shown at 36. The outer end of the pitman is provided with a pin 37 which slidably fits in the above mentioned slot 16 formed in the bottom plate 14. By referring now to Figure 4, it will be seen that 20 a pair of guide bars 38 are arranged on the bottom face of the plate on opposite sides of the slot 16. These guide bars direct the sliding movement of the pin 37 when the pitman is operated by rotation of the disc 21. 25 By now referring to Figure 1, it will be seen that a pair of levers 39 are pivotally connected together by the pivot pin 37. A pair of fulcrum bars 40, relatively short in length, are pivoted as shown at 41, to the 30 bottom plate 14 and are pivoted as shown at 42 to the levers 39. Thus, it will be clear that when the pitman moves the pivot pin 37 to one end of the slot the levers will be spread apart as indicated in dotted lines in 35 Figure 1.

A pair of links 43 are pivotally connected as shown at 44 to the swinging doors 12 and are pivotally connected as shown at 45 to the ends of the levers 43. When the levers are 40 moved by the pitman to the position shown in dotted lines in Figure 1, the links 43 will be moved by the levers to the position shown in dotted lines in Figure 1 and swing the doors outwardly to full open position. Conversely, 45 when the pitman moves the pivot pin in the opposite direction the levers 39 will be returned to the position shown in full lines, carrying the links to the position shown in full lines, thereby closing the doors.

50 In order that the doors may be opened from the exterior of the garage the rope 24 is trained over sheaves 43' secured to the top sill 13 of the door frame and passed through an opening in the garage structure to the 55 exterior of the garage. By now referring to Figure 5 it will be seen that the rope passes through a pipe 44' which is pivotally connected to the garage wall by means of a socket 45 on the wall and a ball 46 on the pipe. The 60 outer end of the pipe is equipped with a reel 47 upon which the rope 24 is wound by means of a crank 48. The reel is provided with a housing 49 which protects the rope from the weather.

65 The rope reel is normally held up out of

the way of traffic by means of an extensible hanger 50. The hanger comprises a pipe 51 which is pivoted to the pipe 44' as shown at 52. A rod 53 is pivoted to the garage wall as shown at 54 and enters the pipe 50. A 70 helical spring 55 surrounds the rod which is terminally equipped with a head 56. The spring 55 normally holds the pipe 51 and the rod 52 in telescoped relationship so that the pipe 44' positions the reel upwardly overhead 75 out of traffic. The dangling rope 57 may be grasped to rock the pipe 44 downward to dispose the reel at the door of the automobile when it is desired to open the swinging doors of the garage. The spring 55 is placed under tension during the movement of the pipe 51 away from the rod 53 and stores up energy to return the reel to initial position when the operator releases the crank after the doors have been opened.

The operation is as follows: Suppose the doors are closed and it is desired to open them from the outside without alighting from the vehicle. The operator pulls down the reel 47 to within convenient reach and turns the 90 crank 48 thereby winding up the rope 24 on the reel and rotating the rope pulley 22 counter-clockwise through approximately half a revolution. The pawl 31 carries the disc 21 counter-clockwise, thereby moving the pitman 35 which in turn carries the pivot pin 37 of the levers to the outer ends of the guides 38. The levers 39 are thereby spread apart to the position shown in dotted lines in Figure 1. The links 43 during this movement of the levers are carried to the position shown in dotted lines in Figure 1 and swing both doors outwardly to open position. The operator now releases the rope reel 47 whereupon the extensible hanger 50 swings the pipe 44' 105 upwardly to dispose the reel out of traffic. The doors are now open and remain open until the operator again operates the rope reel 47 to close the doors. It will be observed that as soon as the operator releases the crank 48 the spring 26 of the rope pulley will return the rope pulley to its initial position thereby unwinding the rope from the reel whereupon all of the parts are in position to be operated again as above described.

To close the doors the operation of the rope reel is repeated as above described, whereby the rope pulley 22 is again rotated counter-clockwise carrying the disc 21 with it to move the pitman 35 through the opposite half cycle. The pivot pin 37 is thereby returned to its initial position shown by full lines in Figure 1 and the levers 37 and links 43 are moved by the pivot pin to the position shown by full lines in Figure 1 to swing the doors closed.

It will be noted that a stop 58 on the pulley engages the plate 17 and limits rotation of the pulley by the rope. The stop serves to halt the pulley in position to permit the 130

pawl 33 to drop in back of either of the teeth 30 or 27 according to whether the doors are being closed or opened as above described.

In order that the doors may be closed 5 from the inside a rope 59 is connected to the main rope 24 and is trained over a sheave 60 at the side of the door. The end of the rope hangs down from the sheave within convenient reach so that the doors may be opened 10 from the inside by pulling the rope.

It will be here noted that the doors are automatically locked in open or closed position by reason of the pitman 36 being slightly off center as shown best in Figure 1. Since 15 the pitman does not quite come to center when there is any strain on the doors tending to close them a backward strain is produced on the ratchet disc 21 and this is resisted by the pawl 33 back of the tooth 27 20 so that no movement of the parts can take place. Consequently, the doors are automatically locked in either open or closed position. The crank 28 furthermore can be locked with a padlock by means of a clip 61 on the 25 pipe 44'. The clip is provided with a hole 62. The padlock (not shown) may be slipped through the hole and around the crank. Consequently, the doors can be opened only by 30 unlocking the padlock on the outside or by pulling the rope 59 on the inside of the garage.

Having thus described the invention, I claim:

1. In a door operating mechanism, the 35 combination with a hinged door, of a support, a shaft rotatably mounted thereon, a rope pulley adapted to rotate said shaft counter-clockwise through one half revolution, a spring adapted to return the pulley 40 to inactive position after each actuation, a ratchet controlled pitman operated by said shaft, and operating connections between said pitman and said door.

2. In a door operating mechanism, the 45 combination with a hinged door, of a support, a shaft rotatably mounted thereon, a spring controlled rope pulley loose on said shaft, a ratchet disc fixed on the shaft, a pawl on the pulley alternately engaging in 50 diametrically opposite teeth on the disc for uniting the disc and pulley for rotation as a unit counter-clockwise through one half revolution, a pitman on said disc, and operating connections between said pitman and said door.

3. In combination, hinged doors, a support above the doors, levers pivotally connected together, the pivot pin of said levers being mounted to slide on said support, fulcrum bars on said support pivotally connected to said levers near said pivot pin and adapted to rock the free ends of the levers towards and away from said doors when said pivot pin is moved, links connected to the 60 free ends of said levers and to said doors

for opening and closing said doors, a rope pulley on said support, and operative connections between said rope pulley and said pivot pin for moving said pin when said pulley is rotated.

4. In a door operating mechanism, the combination of a support, a shaft rotatably mounted thereon, a disc fixed to said shaft and having pairs of ratchet teeth disposed at diametrically opposite points in the periphery of the disc, a rope pulley loose on said shaft, a pawl carried by said pulley and engaging one of said teeth to lock the disc for rotation as a unit with the pulley through one half revolution counter-clockwise, a pawl on said support adapted to engage in another of said teeth and prevent retrograde movement of said disc, a spring adapted to move said pulley clockwise to inactive position after each actuation, and door opening and closing means operated by said disc.

5. In a door operating mechanism, the combination of a support, a shaft thereon, a rope pulley loose on the shaft, a ratchet disk fixed on the shaft and having two pairs of oppositely disposed ratchet teeth on the edge, a pawl carried by the support and adapted to engage one of the teeth of one pair of said ratchet teeth for holding said disk against retrograde movement, a pawl carried by said pulley and adapted to engage the other tooth of said pair of ratchet teeth for locking the disk and pulley for rotation as a unit through one-half revolution, a 100 spring on the shaft for returning the rope pulley to inoperative position after each actuation, a pitman carried by the disk, and means for operatively connecting the pitman to a swinging door.

6. In a door operating mechanism, the combination of a support, a shaft thereon, a rope pulley for rotating the shaft counter-clockwise through one-half revolution, a rope on said pulley, a reel for winding said rope thereon to actuate said pulley, a pivoted arm carrying said reel at the free end thereof, a spring holding said arm normally raised, means carried by the arm for lowering the arm against the tension of the spring to dispose the reel within reach of the operator, a disk fixed on said shaft, a ratchet controlled pitman carried by the disk, and means for operatively connecting the pitman to a 115 swinging door.

7. In a door operating mechanism, the combination with a hinged door, of a support, a shaft rotatably mounted on the support, a rope pulley adapted to rotate said shaft through one-half revolution, a spring 125 on the shaft adapted to return the pulley to inoperative position after each actuation, a ratchet and pawl mechanism on the shaft operated by the pulley, a pitman controlled by said mechanism, guides on the support, and 130

links for operating said door having their ends pivoted together by a common pivot slidably mounted in said guides, said pitman being connected to said pivot and being disposed slightly off-center in inoperative position whereby to produce a backward strain on the ratchet and pawl mechanism, which strain is resisted by said mechanism to lock said hinged door in open or in closed position.

In testimony whereof I affix my signature.
